G. W. OWEN,
DETACHABLE HEEL FOR SHOES AND BOOTS.
APPLICATION FILED OCT. 4, 1920.

1,400,096.

Patented Dec. 13, 1921.

UNITED STATES PATENT OFFICE.

GEORGE W. OWEN, OF INDIANAPOLIS, INDIANA, ASSIGNOR OF ONE-HALF TO PAUL K. THIRY, OF INDIANAPOLIS, INDIANA.

DETACHABLE HEEL FOR SHOES AND BOOTS.

1,400,096.

Specification of Letters Patent.

Patented Dec. 13, 1921.

Application filed October 4, 1920. Serial No. 414,533.

To all whom it may concern:

Be it known that I, GEORGE W. OWEN, a citizen of the United States, residing at Indianapolis, in the county of Marion and 5 State of Indiana, have invented certain new and useful Improvements in Detachable Heels for Shoes and Boots, of which the following is a specification.

My said invention has for its object to 10 provide a detachable heel for shoes and boots, which shall be light, durable, inexpensive, and the separable body of which shall be readily detachable for renewal of the lower wear portion or for replacement by a new 15 body portion. This heel is an improvement on that disclosed in my application No. 364,991, filed March 11, 1920.

Referring to the accompanying drawings which are made a part hereof and on which 20 similar reference characters indicate similar parts,

Figure 1 is a perspective of the heel which is the subject of my invention,

Fig. 2 a vertical section of a heel and a 25 part of the shoe to which it is attached,

Fig. 3 shows the under side of the heel plate, and

Fig. 4 a perspective of the body member.

In the drawings 1 represents the body 30 member of the heel and 2 a plate adapted to be attached to the sole 3 of a shoe or boot by means of bent-up portions 4 of the plate, or other equivalent devices, 5 indicates a nail of which a plurality may be driven through 35 holes 6 in plate 2 for greater security. The body 1 is made hollow at the top and bottom for the sake of lightness and also for economy of material, and is preferably formed of aluminum, this material being light and 40 strong.

A partition 7 separates the upper and lower cavities and pieces of leather 8 and 9 are placed in the lower cavity and constitute substantially a single block. These pieces fit 45 closely in the cavity and are united to the body and to each other by glue or cement. A rubber or leather lift 10 is attached to the bottom of the heel by nails 11 driven into the block consisting of parts 8 and 9.

To the under side of plate 2 a hexagonal block 12 is affixed by rivets 13 or otherwise, or it may be integral therewith. This block has a screw threaded extension in which engages a screw 14 that extends through partition 7 and blocks 8 and 9. An eyelet 17

may be set into the perforation in the blocks as a reinforcement to support the head of the screw.

The block 12 has two opposed long sides and pointed ends and the body 1 has its upper 60 portion hollowed out as shown, so that its forward edge 15 tapers to a knife-edge, and the upper portions at the sides and back are as thin, or thinner than the same parts lower down. A close fit of the upper edges of the 65 metal against the leather sole is thus insured, while economy is also had in the use of the metal. Internal ridges 16 angular to correspond to the angular ends of block 12 are left standing in the hollow upper portion of 70 the heel-body and these ridges and the ends of block 12 are each preferably inclined so that the screw 14 will tend to draw them into close-fitting engagement in spite of slight irregularities. The upper hollowed part in 75 which plate 2 sits may be deep enough to allow the edges of the heel to be forced slightly into the leather if necessary to secure a tight fit between block 12 and ridges 16.

The block 12 and the body member may be formed in a very economical manner, by die casting, to which the shape is well adapted, but I do not limit myself in this regard.

While I have shown a preferred form of 85 my invention I do not limit myself thereto, as various changes falling within the scope of my invention will occur to those skilled in the art. The true scope of the invention is shown by the appended claims.

Having thus fully described my said invention, what I claim as new and desire to secure by Letters Patent, is:

1. In a heel, a plate, a metallic member attached thereto having inclined edges at its 95 ends, and having a screw threaded lug, a hollow metallic body member having ridges within the shell and protected thereby to engage said inclined edges and means to hold the body to the plate, substantially as set forth.

2. In a heel, a detachable body member comprising a hollow shell open at both ends and having a spreading upper portion and upstanding transverse ridges in said portion 105 spaced from and concealed by the upper part of the shell, a side face of each ridge being adapted to engage a similar side face of a part attached to the sole to prevent relative rotation, substantially as set forth.

3. In a heel structure, a plate for attachment to a sole and having a projection depending therefrom, the projection having inclined sides to produce a downwardly tapering formation, a body member comprising a shell, said shell having a thin upper edge closely fitting against the sole, ridges within the outline of the shell having inclined sides to correspond to the sides of the projection on the plate, and means to hold the body to the plate, substantially as set forth.
4. A French heel comprising a plate attachable to a sole and having deep transverse faces and a long threaded lug, a shell having edges adapted to engage a shoe sole, transverse ridges in the shell spaced from its sides, the sides of said ridges engaging like faces on the sole plate, a perforated partition in said shell forming a lower compartment, perforated lift attaching blocks in the compartment, a screw extending through said perforations and engaging the threaded lug, an eyelet in said blocks about said screw, and a lift covering the head of the screw, substantially as set forth.
5. In a heel structure, a plate to be fastened to a sole and having integral points projecting therefrom and also having openings for nails, a hexagonal member fixed thereto having two opposed long sides said member having its shorter sides inclined to produce a downwardly tapering formation and having a screw-threaded socket portion depending therefrom, a body member consisting of a hollow shell having a transverse partition near its lower extremity and up-

standing ridges near the front and rear in its upper portion, said ridges bent to conform to the ends of the hexagonal member, and inclined to conform to the inclined surfaces thereof, and means for holding the body member to the plate, substantially as set forth.

6. In a heel structure, a plate to be fastened to a sole and having integral points projecting therefrom and also having openings for nails, a hexagonal member fixed thereto having two opposed long sides, having its shorter sides inclined to produce a downward taper, and having a screw-threaded socket portion depending therefrom, a body member consisting of a hollow shell having a transverse partition near its lower extremity and upstanding ridges near the front and rear of its upper portion, said ridges bent to conform to the ends of the hexagonal member, and inclined to conform to the beveled surfaces thereof, a perforated block fitting in the lower cavity of the shell and cemented thereto, an eyelet in the perforation, a screw passing through the eyelet and a perforation in the partition and engaging the screw-threaded socket, and a lift fixed to the block, substantially as set forth.

In witness whereof, I have hereunto set my hand and seal at Indianapolis, Indiana, this 21st day of September, A. D. nineteen hundred and twenty.

GEORGE W. OWEN. [L. s.]

Witnesses:

M. L. SHULER,
CAREY S. FRYE.
